UNITED STATES PATENT OFFICE

LLOYD BLACKMORE, OF HIGHLAND PARK, MICHIGAN, ASSIGNOR TO GENERAL MOTORS CORPORATION, OF DETROIT, MICHIGAN, A CORPORATION OF DELAWARE

HORN-BUTTON SWITCH

Application filed November 11, 1927. Serial No. 232,629.

This invention relates to switches and more particularly to switches adapted to be mounted on the top of the steering wheel column of an automotive vehicle for actuating a signal, 5 such as a horn or whistle.

It is an object of my invention to produce a switch of this type which is simple and inexpensive and which is efficient in operation, will retain a clean point of electrical contact 10 and be free from rattle.

Other objects and advantages of the invention will appear in the course of the following description, taken in connection with the accompanying drawing and appended claims.

15 In the drawing:

Figure 1 is a fragmentary longitudinal sectional view taken through the center of a steering wheel embodying my invention.

Figure 2 is an enlarged sectional view of 20 the switch taken on the line 2—2 of Figure 1.

Figure 3 is an exploded view showing the structure and arrangement of the principal parts before assembly.

Figure 4 is a perspective view of the insulating plug carrying the contact member.

Referring to the drawing, I have illustrated a tubular extension 10 at the top of a steering column and above a steering wheel 12 and usual control levers 14 and 16. This 25 extension 10 may or may not rotate with the inner control lever 16 as desired. The extension 10 is shown provided with a converged central portion 18 in which is fixed a hollow shaft 20 extending the length of the steering column. Resting on the central portion 18 is the insulator plug 22 carrying a 35 central metallic contact 24.

The contact 24 is recessed from below and is 40 provided on one side with a threaded aperture in register with a vertical slot 25 in the side of the insulating plug 22. The uninsulated end 26 of an insulated wire, connected with the signal circuit extends upward into the recessed contact 24 and is clamped against 45 the wall thereof by a screw 28 extending into the slot 25 and threaded in the side of the contact 24.

The insulating plug 22 fits snugly in the extension 10 and is held from lateral movement therein. A slot 30 is provided in each

end of the plug, each slot being extended inwardly in its lower portion as shown at 32. The contact member 24 extends slightly above the center of the plug 22, as illustrated, the top of the plug being depressed slightly in 55 the region about the contact 24, as shown at 23. This arrangement provides raised portions 29 adjacent the slots 30.

Resting on the raised portions 29 is a spring 60 fingered disc 34. This disc is substantially circular and is radially cut to provide spring fingers 36. The inner ends of the fingers 36 are located approximately at the edge of the contact 24, thus providing a central opening between the converging finger ends exposing 65 the surface of the contact 24. While I have shown a considerable number of spring fingers it is obvious that four or even two opposed fingers may be considered sufficient.

The disc 34 is held in position by a yoke 70 stamping 38. This yoke is conoidal in shape and is provided with diametrically opposed tabs or projections 40 adapted to fit in the slots 30 and to be crimped in the lower portions 32 of these slots to hold the insulating 75 plug 22, disc 34 and yoke 38 firmly together. The yoke 38 is also provided with a downwardly extending lug 42 provided with a threaded aperture 44. The assembled insulator plug 22, spring washer 34 and yoke 38 80 are held in position within the tubular extension 10 by means of a screw 46 extending through the wall of the extension 10 and threaded into the opening 44 in the lug 42.

Supported on the structure described is 85 the horn button. This button comprises a main portion 48 of suitable insulating material having fixed therein a hollow metallic shank 50. The shank 50 is reduced at 52 and again at 53 to form a tip which extends through the central opening in the yoke 38. I provide a flange on the lower part of the button which comprises a washer 54 having a bevelled upper surface as illustrated. The washer 54 is held on the reduced portion 52 of the shank 50 by riveting or spreading the portion 52 where it is reduced at 53.

The central aperture in the yoke 38 is provided with a bevelled surface corresponding to the upper surface of the washer 54. The 100

spring fingers 36 press upward on the washer 54 and insure that the bevelled upper side will seat snugly in the correspondingly bevelled central portion of the yoke 38. The spring fingers are ordinarily sufficient to hold the button thus firmly seated, but if desired a coil spring 56 may be provided between the under side of the button and the upper side of the yoke 38 and surrounding the shank 50 for insuring that the button will remain seated and will not rattle and yet will require but a light pressure to depress it.

The operation of the device will now be described. When the operator presses the button downward against the resistance of the spring fingers 36, the tip of the shank 50 touches the contact 24 and, due to the contact of the washer 54 with the spring fingers 36 and the yoke 38 which is connected with the metallic part of the framework of the car, the wire 26 connecting with the signalling device is effectually grounded. Upon release of the button, the spring fingers press the shank upward and seat the bevelled surface 54 of the washer in the correspondingly bevelled surface in the central portion of the yoke 38, thus disestablishing contact between the shank 50 and contact 24 and disconnecting the signal circuit.

The button, when in use, will be rotated slightly from time to time and the tip of the shank will thus be cleaned by the grinding thereof on the plug contact. It is also important that electrical contact be made between the tip of the shank and the plug contact as these parts are sufficiently large to withstand a great deal of "sparking" without undue deterioration while the spring fingers can readily carry the current providing they do not "make" and "break" the contact.

I claim:

1. In a horn button assembly, an insulated central contact, an apertured cover, a button having a metallic contact shank extending through said apertured cover over said insulated contact and having a flange extending laterally therefrom, said flange being provided with an upwardly bevelled portion and the central portion of said cover being similarly bevelled to seat said flange, and a spring member fixed between said cover and insulating base and adapted to seat said flange in said aperture.

2. In a horn button assembly, a base of insulating material having a central contact member and a cover provided with a central aperture, a button having a contact shank extending through said aperture over said insulated contact and a flange extending laterally therefrom, said flange being provided with an upwardly bevelled portion and the central portion of said cover being similarly bevelled to seat said flange, and means for

resiliently urging said button upward to seat said flange in said aperture.

3. In a horn button assembly, a base of insulating material having a central contact member and a cover providing with a central aperture, a button having a shank extending through said aperture and a flange extending laterally therefrom, and a disc secured between said base and cover and having a spring finger extending radially therefrom for resiliently urging said button upward to seat said flange against said cover.

4. In a horn button assembly, an insulated base contact, a bridge-piece extending over said contact, a button overspreading said contact and said bridge-piece and having a contact shank extending through said bridge-piece and adapted to engage said base contact and a spring conductor extending from said bridge-piece to said button shank.

In testimony whereof I affix my signature.

LLOYD BLACKMORE.
